(57) **CLAIM**

The ornamental design for a mosquito repellent lamp, as shown and described.

DESCRIPTION

FIG. 1 is a front perspective view of a mosquito repellent lamp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof; and,

FIG. 10 is an enlarged detail view of area 10 in FIG. 2. The evenly broken lines in the drawings illustrate the unclaimed portions of the mosquito repellent lamp, which form no part of the claimed design. The dash-dot-dash broken lines disclose boundaries of the isolated and enlarged views only and form no part of the claim thereof.
